KNIFE HANDLE CONSTRUCTION

Alfred Breitzke, Rockford, Ill.

Application October 23, 1948, Serial No. 56,149

3 Claims. (Cl. 30—125)

1

This invention relates to a handle construction and more particularly to a novel handle construction for a hunting knife and the like.

An object of the invention is to provide a novel handle construction comprising a body portion and a removable head portion wherein the body portion is formed with an axially extending chamber that is sealed when the head is mounted on the body and is accessible when the head is removed and wherein the head portion is formed with a chamber accessible from the exterior of the head portion.

Another object of the invention is to provide a novel handle for a hunting knife or the like in which there is a plurality of axially spaced chambers for the reception of desired and useful items.

Another object of the invention is to provide a novel handle construction having a fluid lighter or the like disposed in a sealed chamber, accessible by the removal of a portion of the handle and a compass or the like disposed in a chamber formed in the removable portion.

Another object of the invention is to provide a novel handle construction that is simple to construct, that is rugged, that is sturdy, that combines both beauty and utility, and that is relatively easy and inexpensive to produce.

Other objects and advantages of the invention will become apparent from the following detailed description taken in connection with the accompanying drawings, in which—

Figure 1 is a side elevational view taken along the longitudinal axis of the knife showing the handle, embodying the present invention, in section;

Fig. 2 is an end view of the handle;

Fig. 3 is a transverse sectional view through the handle taken substantially along the line 3—3 of Figure 1, and

Fig. 4 is a transverse sectional view taken through the handle substantially along the line 4—4 of Figure 1.

Referring now to the drawings, the invention is shown embodied in a handle 11 for a blade 12 of a hunting knife 13. In this embodiment of the invention the handle 11 includes a body 14 and a head 16 detachably mounted on the body.

As shown the body includes a knife guard 17, a collar 18, a generally tubular or sleeve member 19 and a plurality of washers or discs 21 and a collar 22. As best seen in Figures 1 and 4 the forward end of the tubular member 19 is of solid construction and is formed with a vertically extending slot 23 shaped to receive a tang 24 of the

blade 12. The dimensions of the slot 23 and the tang 24 are such as to insure a snug fit between the tang and the tubular member 19. In its assembled position one end of the tubular member 19 abuts against the guard 17 of conventional construction. The latter in turn abuts against the shoulders 26 at the rear end of the blade 12 adjacent the tang 24 and means, such as a pin or rivet 27 extending through the tubular member 19 and the tang 24 secures the tubular member 19, the blade 12 in a rigid assembled relation. With this construction the tubular member 19 in effect defines a chamber 28 extending axially away from the tang end of the blade 12. The collar 18 and the discs 21 are mounted on the tubular member 19 in side by side abutting relation as shown in Figure 1. The collar 18 and the discs 21 may be formed of any suitable material such as leather or metal or as shown herein a combination of metal and leather to obtain a desired ornamental appearance. The collar 22 is threaded on the opposite or rear end of the tubular member 19 as best seen in Figure 1. By varying the axial position of the collar 22 on the tubular member 19 the clamping pressure for securing the knife guard 17, collar 18 and discs 21 in position may be adjusted so that the respective parts are positively in a tightly assembled relation.

The head 16 is formed with a threaded recess 29 shaped to receive the extreme opposite end of the tubular member 19 and a recess 31 facing axially outwardly. A wall 32 separates the recess 29 from the recess 31 so that when the head 16 is threaded on the rear end of the tubular member 19 the chamber 28 in effect is a sealed chamber. Preferably the outer end of the recess 31 is closed by a glass window 33 so that in effect the recess 31 together with the window 33 forms a sealed chamber 34 in spaced axial relation with the chamber 28.

It is readily apparent to those skilled in the art that the chambers 28 and 34 may be utilized for receiving many useful and desirable items, devices, instruments and the like. For purposes of illustration a fluid lighter 36 is shown disposed in the axially extending chamber 28. To prevent corrosion and the like of the tubular member 19 a brass liner 37 may be disposed on the interior of the tubular member 19 to receive the liquid holding material 38 of the lighter 36. As shown in Figure 1 the head end of the lighter 36 is disposed in the threaded recess 29 so that the head 16 in effect forms a cap for the lighter 36. If desired a honing stone may be disposed in the chamber 28 in lieu of the lighter. By way of il-

lustration, a compass 39 is shown disposed in the chamber 34. It is to be understood also that identification means or the like may be disposed in this chamber in lieu of the compass. By disposing a fluid lighter 36 in the chamber 28 of the handle and a compass 39 in the chamber 34 of the handle a knife construction results that has great utility to hunters, trappers, woodsmen, campers and the like.

This handle construction may be readily assembled. For example, to assemble the handle the knife guard 17 is slipped over the tang 24 of the blade 12 to abut against the shoulders 26 and the tang 24 is inserted in the slot 23 formed in the forward end of the tubular member 19. The rivet 27 is then passed through the parts as shown in Figure 1. Thereafter, the collar 18 and the discs 21 are slipped over the tubular member 19. The collar 22 is then threaded on the opposite end of the tubular member 19 and tightened up so that the collar 18 and the discs 21 are held rigidly between the guard 17, which is forced into engagement with the shoulders 26, and the collar 22. The chamber 28 is filled with lighter fluid absorbing material 38 and a lighter 36 is inserted in the accessible end of the chamber 28. The head 16 is then threaded on the outer end of the tubular member 19 and the handle for the knife is complete. The compass may be disposed in the recess 34 either before or after assembly of the head 16 on the body 14.

From the foregoing it is seen that there are many advantages derived from this handle construction including simplicity of manufacture, ruggedness and relatively low cost of production. Moreover, the handle provides a construction in which there are two sealed chambers which are available to a user for any desired use. This handle is particularly meritorious insofar as woodsmen and the like are concerned.

I claim:

1. In combination, a blade having a tang of reduced width defining spaced shoulders, a tubular member having one end formed as a solid portion with a slot extending axially inward from said one end to snugly receive the tang, said tubular member defining an axially extending chamber accessible at the opposite end of the tubular member, means rigidly securing the blade and tubular member together at the tang and said solid portion of the tubular member, a guard mounted on the tang against said shoulders, providing an annular flange extending on opposite sides of the tubular member at said one end thereof, said tubular member having an externally threaded portion at its other end, annular means detachably mounted on the exterior of the tubular member and forming a hand grip, a collar threadedly mounted on said threaded portion of the tubular member spaced from the last-mentioned end and adjustable thereon to clamp

the annular means between it and said flange at said one end of the tubular member, and a chambered head threadedly mounted on said threaded portion of the tubular member beyond the collar adapted to be screwed down against the collar as a stop to close the open threaded end of the tubular member, the chamber in the head forming an extension of the chamber in the tubular member when the head is screwed against the collar.

2. In combination, a blade having an end shaped to define a tang, a tubular member having one end formed as a solid portion with a slot extending axially inward from said one end to snugly receive the tang, said tubular member defining an axially extending chamber accessible at the end of the tubular member opposite to the tang, means extending through the tang and solid portion for rigidly securing the blade and tubular member together, a guard mounted on the tang, a plurality of discs in side by side relation mounted on said tubular member adjacent said guard, a collar threadably mounted on the opposite end of said tubular member to clamp the discs between it and said guard, and a head threadably mounted on the extreme opposite end of the tubular member having a recess in communication with the axially extending chamber, said head forming a seal for said axially extending chamber.

3. In a handle assembly, in combination, a tubular member defining an axially extending chamber closed at one end, means connected to the tubular member at said one end and forming a transverse external shoulder thereat, said tubular member at its other end being formed with an external thread, a plurality of annular discs in side by side relation detachably mounted on the exterior of the tubular member and forming the hand grip of the handle, a collar threadedly mounted on said threaded end of the tubular member and adjustable thereon to clamp the discs between it and said transverse shoulder at said one end of the tubular member, and a head threadedly mounted on the extreme threaded end of the tubular member closing the threaded end of the tubular member and defining a recess communicating with the axial chamber of said tubular member to form an extension thereof.

ALFRED BREITZKE.
